UNITED STATES PATENT OFFICE

EDMUND HOFFMAN, OF BROOKLYN, NEW YORK, ASSIGNOR TO AMERICAN CAN COMPANY, OF NEW YORK, N. Y., A CORPORATION OF NEW JERSEY

GASKET FOR TALCUM POWDER CANS

Application filed May 11, 1928. Serial No. 276,938.

This invention relates to metallic containers but more particularly to containers having sifter tops and which are designed to contain such light, fine powders as talcum powder and the like.

Considerable trouble has always been experienced with containers of this type, due to the fact that when they are filled with a fine powder, such as fine talcum powder, the powder leaks out around the edges of the cover and between the sifter and sifter cap. Heretofore, it has been necessary to make cans of this type with very tight-fitting covers to make them as nearly powder-tight as possible. This has necessitated fitting the contour of the cover exactly with that of the body. In actual construction this requires a precision in the manufacturing equipment which causes considerable and continuous expense in upkeep and manufacture, and even then the containers manufactured have not always been acceptable to the trade. Also, this necessitated the use of but a very few shapes, such as round, oval or oblong; and even with the oblong containers the straight lines on the body required a heavy reinforcement so that the sides and ends would not collapse when the tight fitting covers were applied.

It is the principal object of this invention to provide a container for such powders which will overcome this undesirable leakage.

A further object is the provision of such a container which can be made and furnished to the trade in a more numerous assortment of shapes substantially as economically as the type formerly used.

A further object of this invention is to provide a container which does not require the exact precision in manufacture as was formerly necessary.

A novel feature of my invention is the means of making the container leakproof. Another novel feature is in the way in which the leakproof feature is introduced and engaged by the container to reap the benefit of its use.

Numerous other objects and advantages of the invention will be apparent as it is better

understood from the following description, which, taken in connection with the accompanying drawings, discloses a preferred embodiment thereof.

Referring to the drawings:

Figure 1 is a view of a container with parts broken away to show the assembly;

Fig. 2 is a plan view of a washer used between the cover and the body of the container, and

Fig. 3 is an enlarged detail showing the assembly at the juncture of the top piece, the washer and side walls.

A can 11 of sheet metal of the usual type is provided but at the top edges of the container the inturned peripheral lip 16 is formed. A top member 12 is provided as usual to frictionally engage the body member. The top member is or may be constructed with a shoulder along its outer periphery and the usual flange 21 extending downwardly therefrom. An open type sifter top 13 is firmly secured to this top member. To secure a powder-tight seal closure, I provide a washer 15, having a central aperture 19, which is designed to be interposed between the body member and the top member, the washer 15 having sufficient size to slightly extend beyond the inturned lip formed on the body. This washer may be made of such material as blotting paper or other similar material, which is soft enough to be readily engaged by the inturned lip 16 along the top of the body member. I also provide another washer 17 of the same nature to be interposed between the sifted top 13 and its cap 18.

When the container is assembled as shown in Figure 1, the washer engages between the inturned lip 16 of the body member and the shoulder 14 of the top member, the flange 21 of the top member extending downwardly over and frictionally engaging the side walls of the body member. When the top member is put in place, the portion of the washer 15 extending outwardly beyond the inturned lip 16 of the body member is forced into the groove between the inturned lip and the flange of the top member effectually sealing the contents into the interior and preventing

leakage between the two. This is especially effective at the side seam of the body member, which is the most difficult portion of the container to seal. The necessity for the absolute tight closure between the flange of the top and the side wall of the body formerly necessary is obviated, since the washer actually acts along the shoulder in the top member. The washer 17 between the sifter 10 top and the cap effectually seals the space between these two and prevents leakage at this point.

It is thought that this invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

1. In a container for light fine powders 25 a body member open at the top, a washer of sheet material across the top end of the body member into which the presented top end is indented, and having a hole through which material in the body is discharged 30 from the body, said washer having a wide stiff body portion, and a top closure member having an external flange driven and tightly fitting down over the end of the body and permanently pressing the washer there- 35 against.
2. In a container for light fine powders, a body member having its edges interposed in a side seam, a washer of sheet material having a wide stiff body portion and ar- 40 ranged above the end of the can body and indented by the edge of the body and abut- 45 ting on and closing the end of the side seam and having a hole through which material in the body is discharged from the body and a top closure member having an internal flange driven and tightly fitting down over the end of the body and permanently pressing the washer thereagainst to close said con- 50 tainer against leaking at the end of the side seam.

EDMUND HOFFMAN.
